(57) **CLAIM**

The ornamental design for an ice machine, as shown and described.

DESCRIPTION

FIG. 1 is a front perspective view of an ice machine showing a first embodiment of my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a front perspective view of an ice machine showing a second embodiment of my new design;

FIG. 9 is a front view thereof;

FIG. 10 is a rear view thereof;

FIG. 11 is a left side view thereof;

FIG. 12 is a right side view thereof;

FIG. 13 is a top plan view thereof; and,

FIG. 14 is a bottom plan view thereof.

The evenly broken lines in the drawings depict the unclaimed portions of the ice machine only and form no part of the claimed design.
